UNITED STATES PATENT OFFICE.

WILLIAM A. LURIE, OF CHICAGO, ILLINOIS.

LOCKING-BOLT STRUCTURE.

1,102,527.

Specification of Letters Patent.

Patented July 7, 1914.

Application filed October 24, 1913. Serial No. 796,981.

To all whom it may concern:

Be it known that I, WILLIAM A. LURIE, a citizen of the United States, residing at Chicago, county of Cook, and State of Illinois, have invented a new and useful Improvement in Locking-Bolt Structures, of which the following is a specification:

My invention relates to locks and involves an improved locking bolt structure which cannot be opened except in the regular manner either by the door knob or by a key.

Among the important objects of the invention are to provide a locking bolt which cannot be sprung or forced open as by the insertion of a knife blade or similar implement between the bolt and jamb; to provide a locking bolt of the above character which will not prevent closing or opening of a door in the usual manner; to provide a locking bolt which, when the door is closed or slammed, will expand to thus prevent its forcing, and in general to provide an improved locking bolt of the character referred to which is simple to manufacture and which can be readily substituted for the ordinary bolt in a lock without materially changing the general lock structure.

In the accompanying drawings which clearly illustrate the various features of the invention, Figure 1 is a side elevational view of a lock with the cover plate removed, Fig. 2 is a similar view but showing the bolt drawn, and Fig. 3 is an enlarged sectional view on plane 3—3 Fig. 1.

The lock frame shown comprises the rectangular body 5, the escutcheon plate 6, and a cover plate 7 associated in the usual manner. The escutcheon plate has the opening 8 for the locking bolt 9 whose head *a* is reciprocated in pockets *b* and *c* provided in the body 5 and cover plate 7 respectively. The shank *d* of the bolt has the front and rear studs *e* and *f* extending therefrom, the rear stud *e* pivotally receiving the upper end of bell crank lever 10 fulcrumed at its elbow on the stud 11 extending from the lock body 5, the lower end 10' of the lever being engaged by the inner end of spring 12 anchored at its outer end at 13 to the body 5, the spring tending to swing the lever 10 to hold the bolt 9 in its outer position and to resist inward movement thereof.

The bolt head *a* has the vertical slot 14 therethrough in which and adjacent the ends thereof are pivoted at *g* and *g'* the upper and lower plates 15 and 15' at their outer

ends, these plates being always within the slot. Extending from the upper and lower edges respectively of these plates are detent tongues 16 and 16' respectively whose inner edges are preferably in arcs centered at the pivot pins *g* and *g'* respectively. Reciprocal on the front face of the bolt 9 is a wedge bar 17 having the guide extension 18 on its rear side engaging in the guide groove 19 in the bolt head *a*. The outer end of the bar 17 is pointed to provide the upper and lower wedge surfaces *h* and *h'* for co-operating with the lower and upper edges *i* and *i'* respectively of the plates 15 and 15', outward movement of the bar causing spreading of these plates to carry their detent tongues 16 and 16' outside of the slot 14 and in front of the upper and lower edges of the opening 8 to thus prevent inward movement 75 of the bolt. Suitable springs 20 and 20' anchored to the bolt shank bear at their outer ends against the inner projections *j* and *j'* respectively on the plates 15 and 15' and tend to bring these plates together to draw 80 in the tongues 16 and 16'.

At its inner end the bar 17 forks to receive the stud *f* on the bolt shank, the rear end of the bar being thus guided. Extending rearwardly from the bar is a pin *k* which 85 passes through the longitudinal slot *l* in the shank *d* of the locking bolt and into the path of the lower end of the arm 21 extending from the hub 21' for suitable door knob structure (not shown). A bell crank lever 90 22 has in its upper end the slot 23 receiving the pin *k*, this lever being pivoted at its elbow on the stud 11 which also pivots the lever 10 already described. The lower end 22' of lever 22 is engaged by spring 24 95 anchored at its outer end to the lock body as shown at 13, the spring tending to resist inward movement of the wedge bar 17.

The operation of the mechanism thus far described is apparent. Figs. 1 and 3 show 100 the normal disposition of the parts, the locking bolt being held out by force of spring 12 and the wedge bar being held out by force of spring 24, the detent tongues 16 and 16' being out and in front of the escutcheon 105 plate to prevent inward forcing of the lock bolt. To open the lock the door knob is turned to swing arm 21 against pin *k*, this causing the wedge bar to be drawn inwardly relative to the locking bar until the pin 110 reaches the inner end of the slot *l* whereupon the locking bolt is also drawn in-

wardly, Fig. 2. When the bar 17 moves along its wedge surfaces are withdrawn from the plates 15 and 15', which are then swung together by spring 20 and 20' to draw in the 5 detent tongues to thus allow the inward movement of the bolt when the pin *k* reaches the end of slot *l*. When the knob is released the springs 12 and 24 act on levers 10 and 22 to shift the locking bolt and 10 bar 17 together outwardly until the bolt reaches its normal position, spring 24 then continuing to swing lever 22 until bar 17 has been forced outwardly to spread the plates 15 and 15', the detent tongues 16 and 15' 15 being then again effective to lock the bolt. A suitable stop lug 25 is provided to limit the outward movement of the bolt 9.

Provision must be made to allow inward movement of the locking bolt when the door 20 is swung to closed position without turning the door knob, as when the door is slammed or blown shut. Accordingly a trip plate 26 is provided, this plate being of 25 segment shape and pivoted at its angle on pin 27 extending through the upper end of the horizontal slot 28 in the bolt head *a*. A spring 29 secured to the rear side of the locking bar engages at its outer end with the trip plate and tends to swing it outwardly 30 to hold its outer edge 26' out of the slot 28. The inner edge 26'' is adapted to engage with the outer end of the guide extension 18 on the wedge bar 17 so that when a door is moved to closed position without turning of 35 the door knob the trip plate will strike the jamb plate in advance of the inclined outer face 9' of the bolt, the result being that the wedge bar 17 is shifted inwardly by the trip plate and the plates 15, 15' are swung by 40 their springs to draw in the detent tongues 16, 16' to allow inward movement of the bolt and closing of the door. As soon as the door is entirely closed the bolt will move out and the wedge bar will shift out to effect spreading 45 of plates 15, 15' and locking of the bolt by the projected detent tongues.

The lock shown is also provided with a lock operating push button 30 slidable in opening 31 below the lower ends of the 50 levers 10 and 22. In the normal position of the lock parts the end 10' of lever 10 is a distance above the end 22' of lever 22 in order that, upon depression of the button 30, its end 30' will engage first with lever 55 22 to effect withdrawal of the wedge bar before lever 10 is engaged to effect drawing in of the locking bar, the operation being the same as when the door knob is turned to swing arm 21.

60 I thus provide an improved locking bolt which will not interfere with the closing or opening of a door in the usual manner, and which, when sprung, cannot be forced or opened except in the regular manner by 65 knob or key. The entire structure is very

simple and can readily be installed in ordinary locks.

I do not desire to be limited to the exact construction, arrangement and operation described, as changes and modifications are no 70 doubt possible which would come within the scope of the invention.

I claim as follows:

1. In a lock the combination of a locking bolt having a slot in its head, a plate pivoted in said slot and having a detent tongue extending therefrom, means tending to hold the plate to keep its tongue within the slot, a bar on said bolt normally engaging with said plate to cause the tongue to project beyond the bolt head side to block inward movement of the bolt, and bolt actuating mechanism having connection with said bar to shift said bar to release said plate before effecting inward movement of the bolt. 75 80 85

2. In a lock, a lock bolt, a detent pivoted to the head of said bolt, means tending to hold said detent entirely within the bolt head sides, mechanism on said bolt co-operating with said detent to effect projection 90 thereof beyond the bolt head side to block inward movement of the bolt, and bolt actuating means adapted when actuated to cooperate first with said mechanism to effect withdrawal of the detent before effecting 95 inward movement of said bolt.

3. In a lock, a lock bolt, a plate pivoted within the bolt head, a spring tending to hold the plate entirely within the head, a bar slidable on the lock bolt and engaging 100 with said plate to project same beyond the bolt head side, and actuating mechanism for said lock bolt adapted when actuated to first withdraw said bar to allow said plate to enter the bolt head and then to shift said 105 bolt inwardly.

4. In a lock, a lock bolt, plates pivoted in the head of said bolt, springs tending to hold said plates entirely within said head, a wedge bar slidable on said bolt, means 110 tending to force said bar between said plates to cause spreading thereof and extension beyond the bolt head sides, and actuating means for said bolt adapted when actuated to first withdraw said wedge bar to allow 115 entrance of the plates into the bolt head to release the bolt and then to shift the release bolt inwardly.

5. In a lock the combination of a lock bolt, means tending to hold the bolt out detent plates pivoted in the head of said bolt, means tending to hold said plates entirely within said head, a wedge bar slidable on said bolt, means tending to hold said bar out with its wedge end between said plates to cause said plates to project beyond said bolt head, a pin extending from said bar, said bolt having a slot through which said pin extends, and an actuating arm engaging 125 said pin to shift the bar to release the de- 130

tent plates and to draw the bolt in when said pin reaches the end of said slot.

6. In a lock the combination of a lock bolt, means tending to hold the bar out, a 5 detent plate pivoted in the head of the bolt, a spring tending to hold the plate entirely within said head, a bar slideable on said bolt and extending into said head, means tending to hold said bar in engagement with said 10 plate to cause said plate to project beyond the head side, actuating means connected with both said bar and bolt, and means whereby upon operation of said actuating means said bar is actuated first to release 15 said plate and said bolt then drawn in.

7. In a lock, a lock bolt, pawls pivoted in the head of said bolt and means tending to hold said pawls within the bolt head sides, a bar tending to force said pawls out be- 20 yond the bolt head sides, actuating mecha-

nism for controlling the retractive movement of said bolt and bar and operable to move the bar in advance of the bolt whereby said pawls are first withdrawn to allow movement of the bolt, a tongue pivoted in 25 said bolt head and extending beyond the front face thereof, said bar being in the path of said tongue whereby upon inward movement of said tongue said bar will be shifted in to effect release of said pawls to allow 30 the bolt to move in.

In testimony whereof I have signed my name to this specification in the presence of two subscribing witnesses this 20th day of October, A. D. 1913, at Chicago, Illinois.
